UNITED STATES PATENT OFFICE.

MOE JACOB, OF NEW YORK, N. Y.

LEGGING.

1,085,427.

Specification of Letters Patent.

Patented Jan. 27, 1914.

Application filed January 29, 1913. Serial No. 744,882.

To all whom it may concern:

Be it known that I, MOE JACOB, a citizen of the United States of America, residing in New York, in the borough of Manhattan, 5 county and State of New York, have invented certain new and useful Improvements in Leggings, of which the following is a specification.

This invention relates to a split lapping 10 legging provided with suitable fastening devices.

The object of the invention is to provide a legging of this character which can be easily closed around the leg and which will 15 afford full protection against the ingress of snow and rain.

In the accompanying drawing, Figure 1 represents a side-elevation of my improved legging, Fig. 2 is a horizontal section on line 2, 2, Fig. 1, and Fig. 3 is a detail section 20 through the overlapping portion of the legging, drawn on a larger scale.

Similar letters of reference indicate corresponding parts in the different figures of 25 the drawing.

Referring to the drawing, *a* represents the underlapping portion and *a*¹ the overlapping portion of my improved legging, which is made of the usual shape and material.

30 As the legging is mainly to be used in stormy weather, the material of which the same is made is preferably treated with a waterproofing substance. The legging is open at the outside, the underlapping portion

35 *a* of the same being provided with a reinforcing steel-wire *b*, which is set off at some distance from its edge, while the overlapping portion is likewise provided with a reinforcing wire *b*¹, said reinforcing wires

40 being inclosed by hems formed in the underlapping and overlapping portions of the legging. The legging is provided at its lower and upper ends with eyelets *d*, *d*¹, also at intermediate points of the overlapping

45 portion with a pair of eyelets *d*², while the underlapping portion is provided between the eyelets *d*² and adjacent to its reinforcing wire with a hook *e*. A lacing string *f* is attached to the lower eyelet *d* of

50 the underlapping portion by means of a knot *f*¹ or otherwise, passed over the reinforcing wires of both under- and overlapping portions *a*, *a*¹ and through the eyelet *d* at the lower end of the overlapping portion, then along the under-side of the latter to

the eyelet *d*² at the middle portion of the overlapping portion, then across the reinforcing wires and around the hook *e*, back again over the reinforcing wires and through the second eyelet *d*², then along the under-side of the overlapping portion to the uppermost eyelet *d*¹ of the same, then across the reinforcing wires and through the upper eyelet *d*¹ of the underlapping portion, to which it is tied in any suitable manner. 60

If desired, another pair of eyelets *d*² and hook *e* may be employed at intermediate points between the lower and upper ends of the legging, especially for extra large sizes 65 of leggings. For ordinary smaller sizes one pair of eyelets *d*² and hook *e* are sufficient.

When it is desired to put the legging over the foot and on the leg of the wearer, the lacing string *f* is untied at the upper end, the middle portion of the lacing string removed from the hook and the lower portion of the legging extended sufficiently 75 apart so as to permit the foot to be passed through the legging, the underlapping portion remaining under the stiffening rib of 80 the overlapping portion; when the lacing string is tightened by pulling the same in upward direction over the eyelets and placing the same over the hook *e*, after which the upper end of the string is tied to the eyelet *d*¹ at the upper end of the underlapping portion, as shown in Fig. 1. When the lacing string is drawn the stiffening edge 85

rib of the overlapping portion or flap slides over the underlying portion or flap into 90 abutting contact with the offset stiffening rib of the underlying flap. The underlying flap thus serves as a guide to bring the stiffening ribs in abutting contact and to hold them in that position. The abutting ribs 95 operate jointly with the spaced lacing devices to hold the flaps closed along the spaces between the lacing connections, whereby a multiplicity of eyelets or fastenings is avoided. The abutting stiffening ribs in connection with the underlying flap effect and maintain a complete closing of 100 the legging so that no particle of snow or rain can enter into or settle below the lapping portions thereof. 105

I claim:

A split legging having lapping flaps, the overlapping flap being provided with a stiffening rib at its edge and the underlapping flap passing under said stiffening rib 110

and being itself provided with a stiffening rib offset from its edge, and fastening devices arranged to draw the edge rib of the overlapping flap over said underlapping flap and into abutting contact with said offset rib of the underlapping flap.

In testimony, that I claim the foregoing

as my invention, I have signed my name in presence of two subscribing witnesses.

MOE JACOB.
